UNITED STATES PATENT OFFICE.

JULIUS HENRY BECKER, OF SAN FRANCISCO, CALIFORNIA, ASSIGNOR TO AMERICAN HEAT & POWER CO., OF SAN FRANCISCO, CALIFORNIA, A CORPORATION OF CALIFORNIA.

ATOMIZER FOR OIL-BURNERS.

1,095,447.

Specification of Letters Patent. Patented May 5, 1914.

Application filed March 10, 1913. Serial No. 753,228.

To all whom it may concern:

Be it known that I, JULIUS H. BECKER, a citizen of the United States, residing at San Francisco, in the county of San Francisco and State of California, have invented new and useful Improvements in Atomizers for Oil-Burners, of which the following is a specification.

This invention relates to a gear atomizer 10 for oil burners.

The object of this invention is to provide a simple, compact and efficient mechanism by which heavy fuel oils, such as crude oil, may be thoroughly atomized and mixed with 15 air before being delivered to the combustion chamber of a furnace.

The invention consists of the parts and the construction and combination of parts as hereinafter more fully described and 20 claimed, having reference to the accompanying drawings, in which—

Figure 1 is a plan view partly in section, showing the application of the mechanical atomizer. Fig. 2 is a central, vertical section of Fig. 1. Fig. 3 is a plan view of a 25 pair of feed rolls, showing a modified form of same.

Referring to the drawings: A indicates a nozzle of any suitable construction, in the 30 lower portion of which is formed a recess or pocket 2, to which crude oil or a similar product is delivered through a pipe 3. Suitably journaled with relation to the oil pocket 2, in a pair of cross arms 4, suitably secured 35 in the sides of the nozzle, is a pair of intermeshing spur gears 5 and 6, one of which is secured upon a driving shaft 7, direct connected to an electric motor or similar means, not here shown. Mounted upon the shaft 7 40 is a blower or fan 8, provided for the purpose of producing a forced draft through the nozzle. In operation it can be seen that the gears are so positioned with relation to the oil level in the pocket 2 that the lower 45 periphery or teeth of the gears will be partly submerged in the oil, or will come into sufficient contact with same to elevate a continuous film of oil which is constantly thrown up between the gears in the direction of 50 arrow a, by the centrifugal action of the gears; the thickness of the projected oil film being determined by the relative fit or position of the gears with relation to each other.

55 The thin spray or film of oil thrown up

between the gears is instantly subjected to the forced draft passing through the nozzle, and is thus further broken up or atomized before being discharged from the nozzle tip into the furnace. The oil level within 60 the pocket 2 is entirely controlled by the position of the gears with relation to the oil surface. Any excessive feed of oil through pipe 3 would be instantly picked up both by the peripheral surface and side 65 surfaces of the gears and projected into the forced draft passing through the nozzle, thus insuring against any overflow or back flow from the nozzle.

By referring to Fig. 3, I have shown a 70 pair of contacting rollers, the surfaces of which are grooved or corrugated as shown at 9. The grooved or corrugated surfaces, as shown, are provided for the purpose of increasing the peripheral surface area without increasing the width of the roller.

By referring to Fig. 2, I wish it understood that the fan or blower indicated at 8, in some instances may be entirely eliminated, and that the forced air current may 80 be supplied from any suitable source, as a compressor or like means.

An atomizing burner, constructed as here shown, is simple and compact in construction and automatic and positive in action. 85 The atomizing effect produced by the mechanical and centrifugal action of the feed rollers or gears, together with the forced draft, produces a perfect combustible mixture which burns with an intense flame of 90 corresponding high efficiency.

The materials and finish of the several parts of the burner are such as experience and judgment of the manufacturer may dictate.

I wish it understood that various changes in form and proportions and minor details of construction may be resorted to within the scope of the appended claims, and that I do not wish to limit myself to the specific 100 design and construction here shown.

Having thus described my invention, what I claim and desire to secure by Letters Patent is:

1. In an atomizing oil burner, the combination of a nozzle, means for forcing an air current through the nozzle, a pair of intermeshing gears journaled within the nozzle, means for delivering oil between said gears, and means for revolving the gears 105

110

to centrifugally project the oil delivered between the gears.

2. The combination in an atomizer of a pair of intermeshing revoluble members, means for delivering a fluid to the surface of said members, and means for revolving the members to project the fluid by centrifugal force.

3. The combination in an atomizing oil burner, of a nozzle, means for forcing a current of air through the nozzle, a pocket formed in the nozzle, means for delivering oil to said pocket, a pair of intermeshing gears journaled within the nozzle adapted to contact with the oil delivered to the pocket, and means for revolving the gears to centrifugally project the oil into the air current passing through the nozzle.

4. The combination in an oil burner, of a conduit having a stationary oil reservoir formed therein, said conduit having a discharge orifice on one side of the reservoir

and an air inlet on the other, a fan in the inlet to create an air blast in the direction of the outlet, and centrifugal means in the reservoir operating at the same time to mechanically agitate the oil in the reservoir to project it into the air blast.

5. The combination in an oil burner, of a conduit having an air inlet, an oil inlet and a fuel discharge orifice, a shaft within the conduit, a fan on the shaft for creating an air blast in the direction of the discharge orifice, and intermeshing gears driven from the shaft and arranged to act on the oil from the oil inlet to project the oil into the air blast.

In testimony whereof I have hereunto set my hand in the presence of two subscribing witnesses.

JULIUS HENRY BECKER.
